GARMENT HANGER

Robert Phillips, Roslyn, N.Y., assignor to Warbern
Plastics, Inc., Brooklyn, N.Y., a corporation of New York

Filed July 12, 1963, Ser. No. 75,771

Term of patent 14 years

(Cl. D80—8)

FIG. 1 is a front elevational view of a garment hanger showing my new design;

FIG. 2 is a side elevational view thereof;

FIG. 3 is a top plan view thereof; and

FIG. 4 is an enlarged vertical sectional view on line 4—4 of FIG. 1.

My design for a garment hanger is characterized by the symmetrical loops forming the lower portion thereof.

I claim:

The ornamental design for a garment hanger, as shown and described.
